(57) **CLAIM**

I claim the ornamental design for the asymmetric pen, as shown and described.

DESCRIPTION

FIG. 1 is a front elevational view of the asymmetric pen of the present invention.

FIG. 2 is a rear elevational view thereof.

FIG. 3 is a top view thereof.

FIG. 4 is a bottom view thereof.

FIG. 5 is a left side view thereof; and,

FIG. 6 is a right side view thereof.
